CLAIM

The ornamental design for the riser for an exercise platform, as shown and described.

DESCRIPTION

FIG. 1 is a top plan view of an riser for an exercise platform of the present invention;

FIG. 2 is a bottom plan view of the riser for an exercise platform of FIG. 1;

FIG. 3 is a side elevational view of the riser for an exercise platform of FIG. 1, the other side elevational view being a mirror image thereof;

FIG. 4 is an end elevational view of the riser for an exercise platform of FIG. 1, the other end elevational view being a mirror image thereof; and,

FIG. 5 is an isometric view of the riser for an exercise platform of FIG. 1.

The broken lines depict portions of the riser for an exercise platform that form no part of the claimed design.
